UNITED STATES PATENT OFFICE

137,410

DESIGN FOR A HUNTING KNIFE

Olaf C. Naugle, Marion, Ind.

Application November 1, 1943, Serial No. 111,563

Term of patent 7 years

To all whom it may concern:

Be it known that I, Olaf C. Naugle, a citizen of the United States, residing at Marion in the county of Grant and State of Indiana, have invented a new, original, and ornamental Design for a Hunting Knife, of which the following is a specification, reference being had to the accompanying drawing, forming a part thereof.

In the drawing

Fig. 1 is a side elevation of a hunting knife showing my new design.

Fig. 2 is an end elevation of the knife looking at the blade end thereof.

The dominant feature of my design resides in the handle shown in full lines.

I claim:

The ornamental design for a hunting knife, as shown and described.

OLAF C. NAUGLE.
